UNITED STATES PATENT OFFICE

142,800

DESIGN FOR A CHAIR SEAT-BACK UNIT

Robert C. Watson, Bryn Mawr, Pa., assignor to
Vidal Corporation, Camden, N. J., a corpora-
tion of Delaware

Application March 8, 1945, Serial No. 118,334

Term of patent 14 years

(Cl. D15—8)

To all whom it may concern:

Be it known that I, Robert C. Watson, a citizen of the United States, residing in Bryn Mawr, County of Montgomery, State of Pennsylvania, have invented a new, original, and ornamental Design for Chair Seat-Back Unit, of which the following is a specification, reference being had to the accompanying drawing, which forms a part thereof.

Fig. 1 is a perspective view of a chair seat-back unit showing my design.

Fig. 2 is another perspective view of the unit viewed from a different angle.

I claim:

The ornamental design for a chair seat-back unit, as shown.

ROBERT C. WATSON.
